(73) Assignee: Suncast Corporation, Batavia, IL (US)

(57) CLAIM

() Term: 14 Years

The ornamental design for a stackable front entry storage tote, as shown and described.

DESCRIPTION

(21) Appl. No.: 29/206,317

FIG. 1 is a perspective view of the stackable front entry storage tote of the instant invention with lid closed;

(22) Filed: May 28, 2004

FIG. 2 is a front view thereof;

(51) LOC (8) Cl. 03-01

FIG. 3 is a left side view thereof;

(52) U.S. Cl. D3/294; D3/273

FIG. 4 is a right side view thereof;

(58) Field of Classification Search D3/273,

FIG. 5 is a top view thereof;

D3/272, 294, 302; D9/420, 423, 425; 206/501,

FIG. 6 is an exploded front view with lid detached;

206/503, 508, 509, 511; 280/47.18; 220/780;

FIG. 7 is an exploded back view of FIG. 6;

D34/40

FIG. 8 depicts FIG. 1 with the lid open;

See application file for complete search history.

FIG. 9 depicts a first storage tote on top of a second storage tote, the broken line showing of the first storage tote is for illustrative purposes only and forms no part of the claimed design.

(56) References Cited

FIG. 10 depicts two stacked storage totes, the broken line showing of the upper storage tote is for illustrative purposes only and forms no part of the claimed design; and,

U.S. PATENT DOCUMENTS

FIG. 11 depicts two stacked storage totes.
